UNITED STATES PATENT OFFICE

2,296,265

LAUNDRY APPARATUS

William J. Russell, Mansfield, Ohio, assignor to Westinghouse Electric & Manufacturing Company, East Pittsburgh, Pa., a corporation of Pennsylvania

Application January 19, 1940, Serial No. 314,577

2 Claims. (Cl. 68—3)

My invention relates to laundry apparatus and has for an object to provide improved apparatus of this kind.

A further object of the invention is to facilitate the loading and unloading of a machine for washing fabrics and centrifuging water therefrom.

A further object of my invention is to provide a loading shelf for laundry apparatus of the type set forth which may be employed as a closure for the access opening of the casing enclosing the washing mechanism.

These and other objects are effected by my invention as will be apparent from the following description and claims taken in accordance with the accompanying drawings forming a part of this application, in which:

Figs. 1 and 2 are perspective views of a laundry machine constructed in accordance with my invention, the former showing the machine during inactive periods thereof and the latter showing the machine during operating periods;

Fig. 3 is a longitudinal vertical sectional view taken through the washing machine shown in Figs. 1 and 2, certain portions of this view being shown in elevation for the sake of clearness; and,

Fig. 4 is a view of a hinge detail shown in Fig. 3.

Referring now to the drawings, the washing apparatus includes a tub structure 10 generally of frusto-conical formation and having an access opening 11 formed in an end wall thereof. A rotatable perforate basket 12 also of frusto-conical configuration is disposed within the tub 10 for containing the fabrics to be washed. The basket 12 includes an access opening 13 aligned substantially with the access opening 11 of the tub. The basket is arranged substantially concentrically within the tube and is rotatable about an axis disposed at an acute angle to the vertical. The washing machine which I have disclosed is shown by way of example but it will be understood that my invention may be applied equally well to other forms of washers wherein the axis of the basket extends in a generally horizontal direction. A washer of the type disclosed herein is shown and claimed in the copending application of Frank Breckenridge, Serial No. 203,804, filed April 23, 1938, and assigned to the assignee of the present application.

Referring particularly to Fig. 3, the basket 12 is rotated by a motor 14 carried in any suitable manner by the tub structure 10 and belted as shown at 15 to a two-speed mechanism 16 carried by an end wall of the tub. The two-speed mecha-

nism drives the basket at relatively low speed for washing the fabrics and at relatively high speed for extracting fluid therefrom. The two-speed mechanism 16 is adjustable in any well understood manner for providing the washing and centrifuging speed. A two-speed mechanism of the type shown assembled to a washer and spinner is disclosed and claimed in the copending application of Frank Breckenridge, Serial No. 305,512, filed November 21, 1939 and assigned to the assignee of the present application. Agitation of the fabrics within the basket during the washing period is effected by a plurality of circumferentially spaced baffles or vanes, one of which is shown at 17, or by other suitable means. The specific vane structure which I have shown is disclosed and claimed in the copending application of Stuart R. Baird, Serial No. 268,103, filed April 15, 1939 and assigned to the assignee of the present application.

Water is admitted to the tub by means of a conduit 18 which terminates in a nozzle 19, the latter directing the water through the access opening 13 into the basket and tub. Water is discharged from the tub through a drain opening 21 forming the bottom thereof, the latter communicating with the inlet of a pump 22 that may be driven by the motor 14 as shown. A suitable valve 23 controls the passage of water from the drain opening 21 to the pump 22 and the water discharged by the pump is conveyed to a point of discharge by means of a flexible conduit 24.

The access opening 11 of the tub structure is closed by a suitable gasketed door 25 hinged in any well understood manner to the tub 10 and latched shut to provide a water-tight connection between the door and the tub during periods when water is contained within the tub. Preferably, the door 25 has a glazed central portion 26 for permitting the operator to view the washing action during operating periods.

From the foregoing description it will be apparent that the tub structure 10, the motor 14, and the two-speed mechanism 16 define elements of a unitary structure which may be supported in any well understood manner. As shown, the unitary structure is carried by a plurality of resilient springs 27 which permit vibration of the structure relative to the foundation supporting the same. Preferably, three springs are employed, two at the front of the washer, and one at the rear for providing a three-point support. A resilient mounting of the general type shown is disclosed and claimed in the application of Frank Breckenridge et al., Serial No.

303,202, filed November 7, 1939 and assigned to the assignee of the present application.

The tub structure 18 is enclosed in a housing 28 which defines a support for the springs 27 and which includes a front wall 29, the upper portion of which is inclined as shown at 31. The inclined portion 31 of the front wall slopes upwardly and rearwardly and is preferably disposed in a plane normal to the axis of the basket. In accordance with my invention, the front wall portion 31 is provided with a depressed rectangular portion 30 having formed therein an opening 32 which registers with the opening 11 of the tub structure. The opening 32 may be circular, as shown, and its diameter is greater than the overall dimension of the door 25 so that the latter may be swung upwardly therethrough. During inactive periods of the apparatus, the opening 32 is closed by a suitable cover 33 which is hinged adjacent its lower margin to the front wall 29 of the casing as generally shown at 34.

The hinge 34 may be of any suitable construction, and, as shown, includes a pintle 35 carried by the casing and supporting a movable hinge bracket 36 which is secured to the cover 33. During active periods of the washer, the cover 33 is swung from the position shown in Fig. 1 to a substantially horizontal position as shown in Fig. 2, for facilitating loading and unloading of the washer. The cover 33 therefore defines a loading shelf in its open position and is retained in the open position in any well understood manner such as, for example, by an ear 37 formed on the bracket 36 and engageable in the open position of the cover with a pad 38 forming a part of the housing 29. In its closed position, the cover is retained by gravity or may be latched shut in any manner well understood in the art.

The outer side of the cover 33 or the side in view when the cover is closed (Fig. 1) may be ornamental to provide a pleasing appearance. When the machine is to be operated, the operator first lowers the cover 33 which defines a shelf that is readily accessible to the operator during loading and unloading of the machine. The door 25 is actuated to its open position and the load is then inserted in the basket 12. The machine is adjusted to effect the washing operation and subsequently to centrifuge the water from the fabrics. As these operations form no part of the present invention, no detailed description of the same is deemed necessary. The control switch for the apparatus is preferably located on the front of the apparatus as shown at 39 where it is convenient to the operator for adjustment after loading the machine. After the centrifuging operation is completed, the door 25 is opened and the operator has a convenient shelf or table adjacent upon which to deposit the damp load removed from the washer. The operator may immediately insert a second load

in the machine and start the same after which the damp load is removed from the shelf and placed on the line for further drying.

Preferably, the shelf is of such width that the operator may stand at the side thereof and adjacent the front wall of the washer so that servicing of the washer may be effected without reaching or bending. In this connection, it will be understood that the cover may be wider than shown if desired, but I prefer to have at least one side edge thereof adjacent the tube opening so that excessive reaching on the part of the operator when removing the damp fabrics from the tub is unnecessary.

While I have shown my invention in but one form, it will be obvious to those skilled in the art that it is not so limited, but is susceptible of various changes and modifications without departing from the spirit thereof, and I desire, therefore, that only such limitation shall be placed thereupon as are specifically set forth in the appended claims.

What I claim is:

1. In a washer, the combination of a casing structure having an opening formed in a front wall thereof, a water-containing tub having its axis extending in a generally horizontal direction and having an access opening in a wall thereof substantially in registry at all times with said first-mentioned opening, a door closing the opening in the tub and preventing spillage of water therefrom, a second door hinged adjacent its lower margin to the casing and closing the opening therein in one position, said second door being movable to a substantially horizontal position for defining a shelf on the front of the casing, and means for retaining the casing door in its horizontal position.

2. In washing apparatus, the combination of a fluid-containing tub structure having a front wall disposed in a plane inclined from the vertical and horizontal, said wall having an access opening formed therein, a door closing said opening and preventing discharge of fluid through said opening during operation of the washing apparatus, a casing enclosing said fluid-containing tub structure and having a front wall portion spaced from and disposed substantially parallel to said inclined front wall of the tub structure, said front wall portion of the casing having an access opening therein registering with the access opening of the tub structure at all times, a second door carried by the casing and movable to a first position for closing the access opening in the casing, said door being movable to an open position wherein it is disposed substantially horizontal for defining a shelf on the front of the casing, and means for retaining the casing door in its horizontal position.

WILLIAM J. RUSSELL.
